UNITED STATES PATENT OFFICE.

GEORGE P. WIGGINTON, OF KALAMAZOO, MICHIGAN, ASSIGNOR TO KALAMAZOO LOOSE-LEAF BINDER COMPANY, OF KALAMAZOO, MICHIGAN.

TEMPORARY BINDER OR LOOSE-SHEET HOLDER.

1,104,855.

Specification of Letters Patent. Patented July 28, 1914.

Application filed March 3, 1913. Serial No. 751,915.

To all whom it may concern:

Be it known that I, GEORGE P. WIGGINTON, a citizen of the United States, residing at Kalamazoo, Michigan, have invented certain new and useful Improvements in Temporary Binders or Loose-Sheet Holders, of which the following is a specification.

This invention relates to improvements in temporary binders or loose sheet holders.

10 This invention relates particularly to temporary binders or loose sheet holders of the type shown in Letters Patent, #851,276, issued to Harry F. Bushong, April 23, 1907, and is a modification, and in some respects, 15 an improvement upon the structure of that patent.

The main objects of this invention are: First, to provide in a temporary binder or loose sheet holder, an improved structure, 20 which is capable of withstanding heavy strains and severe usage without likelihood of becoming inoperative, and one in which the adjusting mechanism and binding members may be repaired should occasion require without materially disturbing the binding. Second, to provide an improved temporary binder or loose sheet holder of the type described, in which the tension on the binding strips is not materially varied 25 by the opening of the book or the swinging of its covers.

Further objects, and objects relating to structural details will definitely appear from the detailed description to follow.

30 I accomplish the objects of my invention by the devices and means described in the following specification.

The invention is clearly defined and pointed out in the claims.

40 A structure which is a preferred embodiment of my invention is clearly illustrated in the accompanying drawing forming a part of this specification, in which:

Figure I is a perspective view of a structure embodying the features of my invention. Fig. II is a longitudinal section on a line corresponding to line 2-2 of Fig. I. Fig. III is an inside plan view, the frames or skeletons only of the covers being shown. 45 Fig. IV is a detail view showing the inside view of the complete cover 2. Fig. V is an enlarged perspective view of the clamping member bar 9 and one of the rods 13 of the clamping member supports. Fig. VI is a detail transverse section on a line correspond-

ing to line 6-6 of Fig. IV, showing the details of the back strip securing means. Fig. VII is a detail section on a line corresponding to line 7-7 of Fig. III, the back strip 7 being omitted. Fig. VIII is a detail section on a line corresponding to line 8-8 of Fig. VII.

In the drawing similar reference characters refer to similar parts throughout the several views, and the sectional views are taken looking in the direction of the little arrows at the ends of the section lines.

Referring to the drawings, the covers 1 and 2 are made up of rectangular frames 3 with outer metal walls 4 and inner walls 5 providing chambers in the covers. A suitable binding 6 of leather or canvas is provided. The chambers in the covers open at the inner ends thereof to receive the back strip 7 and the binding member supports, 75 as will be described.

The clamping members or clamping bars designated generally by the numeral 8 in Fig. I, consist of the metal bars 9 and the reinforcing or backing strips 10. The bars 9 are provided with strap-like pivot loops or knuckles 11 on their rear sides and rearwardly projecting pivot ears 12. The rods 13 of the clamping bar supports are provided with laterally-turned pintles 13' at 85 their projecting ends engaging these pintle loops or knuckles 11. The inner ends of the rods 13 are connected to the cross pieces 14 which engage the outer ends of the covers, the covers being provided with openings 16 between the inner walls and the outer end pieces to receive the cross pieces 14,—see Fig. II.

The supports are adapted to be slipped into the cover chambers from the inner ends 95 of the covers, the cover frame being cut away at 17 to receive the rods 13 and the binding strips 18,—see Fig. III.

The binding strips 18 are preferably of leather in the form of flat thongs and extend 100 between the covers and through slots 19 in the clamping member bars 9, the slots being aligned with the pintles 13'.

The adjusting mechanism for the binding strips is arranged in the chamber of the 105 cover 2 and consists of the bar-like adjusting member 20 with which the screw 21 has threaded engagement, the member 20 being provided with a nut member 22 arranged thereon as shown in Fig. III.

The screw 21 is rotatably supported in a suitable bearing 23 on the cross piece 14. The cover is provided with a keyhole 24, the screw being rotated by means of a removable key. At their other ends, the binding strips are secured to the cross piece 14 of the support in the other cover.

The covers are pivoted upon the binding strips, they being provided with rigid hinge members 25 connected to the pivot ears 12 by suitable pintles.

The backing strips 10 are cut away to receive the binding strips 18 and the support rods 13 and the hinge members so as to permit free pivotal movement of the binding members and covers.

The slots 19 for the binding strips are of such size that the binding strips slide freely therein but are supported against substantial lateral swinging movement thereby so that the binding strips flex at the rear of the bars 9 and in substantially the plane of the pivots for the binding members to the supports and covers. With the parts thus arranged, the tension on the binding strips is not substantially varied by the swinging of the covers or by the movement of the clamping bars when the book is opened or closed or otherwise manipulated.

The back strip 7 is connected to the cross piece 14 in the cover 1 by means of the coiled springs 26. It is adjustably connected to the other cover by means of studs 27 arranged through longitudinal slots 28 in the inner wall of the cover, — see Fig. VI — the heads of the studs serving as finger pieces. The edges of the slots are notched or toothed to receive the studs so that the backing is adjustably connected to the cover. With the back strip thus arranged, the springs 26 yield sufficiently for the normal adjustment of the binder in inserting or removing a few sheets or leaves and when considerable expansion or retraction of the binder is necessary on account of the addition or removal of considerable numbers of leaves, the back strip is correspondingly adjusted by means described.

The binding mechanism is so supported that the covers are largely relieved of strain and great care and skill is not required in the manufacture and assembling of parts. Further, the binding member supports may be made separate from the cover, which is of substantial advantage in manufacturing.

I have illustrated and described my improvements in detail in the form in which I have embodied the same. While considerable variation in structural details is possible, I have not attempted to illustrate or describe the same herein as I believe the disclosure made will enable those skilled in the art to which this invention relates to adapt the same as conditions or taste may indicate.

Having thus described my invention what

I claim as new and desire to secure by Letters Patent is:

1. The combination of the chambered covers; clamping members comprising flat metal bars having strap-like knuckles and pintle ears on their rear sides and longitudinal slots therein alined with said knuckles; supports comprising rods having laterally turned pintles engaging said knuckles on said clamping member bars and cross pieces to which the outer ends of said rods are secured, said supports being arranged in the cover chambers with their cross pieces in engagement with the outer ends of the covers; hinge members connecting said covers to said pintle ears; a binding strip adjusting member; a rotatable screw carried by the cross piece of one of said clamping member supports and having threaded engagement with said adjusting member, the cover containing the screw having a key opening in alinement with the screw; binding strips extending between the covers and through said slots in said clamping member bars, said binding strips being connected to said adjusting member and to the clamping member support cross piece in the other cover; and a back strip telescoping into said cover chambers and having a yielding connection to the support cross piece to which the binding strips are connected, the cover containing the adjusting screw having longitudinal slots in its inner wall, the edges of the slots being notched, and studs arranged in said slots and secured to said back strip whereby said back strip is adjustably connected to the cover.

2. The combination of the chambered covers; clamping members comprising flat metal bars having strap-like knuckles and pintle ears on their rear sides and longitudinal slots therein alined with said knuckles; supports comprising rods having laterally turned pintles engaging said knuckles on said clamping member bars and cross pieces to which the outer ends of said rods are secured, said supports being arranged in the cover chambers with their cross pieces in engagement with the outer ends of the covers; hinge members connecting said covers to said pintle ears; a binding strip adjusting member; a rotatable screw carried by the cross piece of one of said clamping member supports and having threaded engagement with said adjusting member, the cover containing the screw having a key opening in alinement with the screw; and binding strips extending between the covers and through said slots in said clamping member bars, said binding strips being connected to said adjusting member and to the clamping member support cross piece in the other cover.

3. The combination of the chambered covers; clamping members comprising flat

- metal bars having knuckles on their rear sides and longitudinal slots therein alined with said knuckles; supports comprising rods having pintles engaging said knuckles 5 on said clamping member bars and cross pieces to which the outer ends of said rods are secured, said supports being arranged in the cover chambers; hinge members connecting said covers to said clamping members; 10 a binding strip adjusting member; a rotatable screw carried by the cross piece of one of said clamping member supports and having threaded engagement with said adjusting member; binding strips extending 15 between the covers and through said slots in said clamping member bars, said binding strips being connected to said adjusting member and to the clamping member support cross piece in the other cover; and a 20 back strip telescoping into said cover chambers and having a yielding connection to the support cross piece to which the binding strips are connected, and an adjustable connection to the other cover.
4. The combination of the chambered covers; clamping members comprising flat metal bars having knuckles on their rear sides and longitudinal slots therein alined with said knuckles; supports comprising 25 rods having pintles engaging said knuckles on said clamping member bars and cross pieces to which the outer ends of said rods are secured, said supports being arranged in the cover chambers; hinge members connecting said covers to said clamping members; a binding strip adjusting member; a rotatable screw carried by the cross piece of one of said clamping member supports and having threaded engagement with said 30 adjusting member; and binding strips extending between the covers and through said slots in said clamping member bars, said binding strips being connected to said adjusting member and to the clamping member support cross piece in the other cover.
5. The combination of the chambered covers; clamping members; supports comprising rods on which said clamping members are pivotally mounted and cross pieces to which the outer ends of said rods are secured, said supports being arranged within the cover chambers, the covers being hinged to said clamping members; a binding strip adjusting member; a rotatable screw carried by the cross piece of one of said clamping member supports and having threaded engagement with said adjusting member; binding strips extending between the covers and through said clamping members, the openings in said clamping members for said binding strips being in alinement with the pivot connections for said binding members to said support rods, said binding strips being connected to said adjusting member and to the cross piece of the clamping member support in the other cover.
6. The combination of the chambered covers; clamping members; supports comprising rods on which said clamping members are pivotally mounted and cross pieces to which the outer ends of said rods are secured, said supports being arranged within the cover chambers, the covers being hinged to said clamping members; a binding strip adjusting member; a rotatable screw carried by the cross piece of one of said clamping member supports and having threaded engagement with said adjusting member; binding strips extending between the covers and through said clamping members, the openings in said clamping members for said binding strips being in alinement with the pivot connections for said binding members to said support rods, said binding strips being connected to said adjusting member and to the cross piece of the clamping member support in the other cover.
7. The combination of the chambered covers; clamping members; supports on which said clamping members are pivotally mounted arranged within the cover chambers, the covers being hinged to said clamping members; a binding strip adjusting member; a rotatable screw carried by one of said clamping member supports and having threaded engagement with said adjusting member; binding strips extending between the covers, said binding strips being connected to said adjusting member and to the clamping member support in the other cover; and a back strip telescoping into said cover chambers and having an adjustable connection to the cover containing the binding strip adjusting mechanism and a yielding connection to the support in the other cover.
8. The combination of the chambered covers; clamping members; supports on which said clamping members are pivotally mounted arranged within the cover chambers, the covers being hinged to said clamping members; a binding strip adjusting member; a rotatable screw carried by one of said clamping member supports and having threaded engagement with said adjusting member; and binding strips extending between the covers, said binding strips being connected to said adjusting member and to the clamping member support in the other cover.
9. The combination of the chambered covers; clamping members; supports on which said clamping members are pivotally mounted

ed arranged within the cover chambers, the covers being hinged to said clamping members; a binding strip adjusting mechanism carried by one of the clamping member supports; binding strips extending between the covers and through said clamping members, the openings in said clamping members for said binding strips being in alinement with the pivot connections for said binding members to said supports, said binding strips being connected to said adjusting mechanism and to the clamping member support in the other cover; and a back strip telescoping into said cover chambers and having an adjustable connection to the cover containing the binding strip adjusting mechanism and a yielding connection to the binding member support in the other cover.

10. The combination of the chambered 20 covers; clamping members; supports on which said clamping members are pivotally mounted arranged within the cover chambers, the covers being hinged to said clamping members; a binding strip adjusting 25 mechanism carried by one of the clamping member supports; and binding strips extending between the covers and through said clamping members, the openings in said clamping members for said binding strips being in alinement with the pivot connections for said binding members to said supports, said binding strips being connected 30 to said adjusting mechanism and to the clamping member support in the other cover.

11. The combination of the chambered 40 covers; clamping members; supports on which said clamping members are pivotally mounted arranged within the cover chambers, the covers being hinged to said clamping members; a binding strip adjusting mechanism carried by one of the clamping member supports; binding strips extending 45 between the covers, said binding strips being connected to said adjusting mechanism and to the clamping member support in the other cover; and a back strip telescoping into said cover chambers and having an adjustable connection to the cover containing the binding strip adjusting mechanism and a yielding connection to the binding member support in the other cover.

12. The combination of the chambered 55 covers; clamping members; supports on which said clamping members are pivotally mounted arranged within the cover chambers, the covers being hinged to said clamping members; a binding strip adjusting mechanism carried by one of the clamping member supports; and binding strips extending 60 between the covers, said binding strips being connected to said adjusting mechanism and to the clamping member support in the other cover.

13. The combination with the chambered 65 covers; clamping members comprising flat metal bars having strap-like knuckles and pintle ears on their rear sides and longitudinal slots therein alined with said knuckles; supports arranged in said cover 70 chambers and comprising rods having laterally turned pintles engaging said knuckles on said clamping members; hinge members connecting said covers to said pintle ears; binding strips extending between the covers 75 and arranged through said slots in said clamping members; and an adjusting mechanism for said binding strips supported by the clamping member support in one of said covers, the binding strips being connected to 80 the clamping member support in the other cover.

14. The combination with the chambered 85 covers; clamping members comprising flat metal bars having knuckles on their rear sides and openings therein alined with said knuckles; clamping member supports arranged in said covers and provided with pintles engaging said knuckles on said clamping members, said covers being hinged 90 to said clamping members, the axes of the cover hinges being in alinement with the axes of the clamping member pintles; binding strips extending between the covers and arranged through said slots in said clamping bars; and an adjusting mechanism for 95 said binding strips supported by the clamping member support in one of said covers, the binding strips being connected to the clamping member support in the other cover. 100

15. The combination with the chambered 105 covers; clamping members; binding strips extending between the covers and arranged through slots in said clamping members; supports on which said clamping members 110 are pivotally mounted arranged in said cover chambers, said covers being hinged to said clamping members, the axes of the clamping member pivots and the cover pivots being in alinement and in alinement with the plane in which the binding strips are flexed as the clamping bars and covers are moved on their pivots relative to each other whereby the tension of the binding strips is not varied by such movement; and an adjusting mechanism for said binding strips supported by the clamping bar support in one of the covers, the binding strips being connected to the clamping bar support in the other cover. 115

16. In a temporary binder, the combination 120 of the chambered covers; a binding mechanism constituting an adjustable connection for said covers; a back strip telescoping into said cover chambers having a yielding connection to one cover, the inner wall of the chamber in the other cover being longitudinally slotted, the edges of the slots being notched; and studs arranged in said 125

- slots and secured to said back strip whereby said back strip is adjustably connected to the cover.
17. The combination of the chambered covers; clamping members; supports on which said clamping members are pivotally mounted arranged within the cover chambers; a binding strip adjusting mechanism carried by one of the clamping member supports; and binding strips extending between the covers, said binding strips being connected to said adjusting mechanism and to the clamping member support in the other cover.
18. The combination of the chambered covers, clamping members comprising bars having strap-like knuckles and pintle ears on their rear sides and longitudinal slots therein alined with said knuckles, supports comprising rods having laterally turned pintles engaging said knuckles on said clamping bars and cross pieces to which the outer ends of said rods are secured, said supports being arranged in the cover chambers with their cross pieces in engagement with the outer ends of the covers, hinge members connecting said covers to said pintle ears, and binding strips extending between the covers and through said slots in said clamping bars.
19. The combination of the chambered covers, clamping members comprising bars having knuckles on their rear sides and longitudinal slots therein alined with said knuckles, supports comprising rods having pintles engaging said knuckles on said clamping bars and cross pieces to which the outer ends of said rods are secured, said supports being arranged in the cover chambers with their cross pieces in engagement with the outer ends of the covers, and binding strips extending between the covers and through said slots in said clamping bars.
20. The combination of the covers, clamping members comprising flat metal bars having strap-like knuckles and pintle ears on their rear sides and longitudinal slots therein alined with said knuckles, support rods carried by said covers and having laterally turned pintles engaging said knuckles on said clamping bars, hinge members connecting said covers to said pintle ears, and binding strips extending between the covers.
21. The combination of the covers, clamping members comprising flat metal bars having knuckles on their rear sides and longitudinal slots therein alined with said
- knuckles, supports formed independently of and carried by said covers and having pintles engaging said knuckles on said clamping bars, and binding strips extending between the covers.
22. The combination with the covers, clamping members having knuckles and pintle ears on their rear sides and slots therein, alined with said knuckles, supports carried by said covers having pintles engaging said knuckles, hinge members connecting said covers to said pintle ears, and binding strips extending between the covers and arranged through said slots in said clamping members.
23. The combination with the covers, clamping members, binding strips extending between the covers and arranged through slots in said clamping members, supports on which said clamping members are pivotally mounted carried by said covers, the axes of the clamping members being in alinement with the planes in which the binding strips are flexed as the clamping bars and covers are moved on their pivots relative to each other whereby the tension of the binding strips is not varied by such movement, and an adjusting mechanism for the binding strips supported by one of the clamping bar supports, the binding strips being connected to the clamping bar support carried by the other cover.
24. The combination of the chambered covers, clamping members having knuckles and pintle ears on their rear sides and slots therein alined with said knuckles, supports having pintles engaging said knuckles on said clamping bars arranged in the cover chambers, hinge members connecting said covers to said pintle ears, and binding strips extending between the covers and through said slots in said clamping bars.
25. The combination of the covers, clamping members having knuckles on their rear sides and slots therein alined with said knuckles, supports having pintles engaging said knuckles on said clamping member bars carried by said covers, hinge members connecting said covers to said clamping members, and binding strips extending between the covers.
- In witness whereof, I have hereunto set my hand and seal in the presence of two witnesses.
